UNITED STATES PATENT OFFICE

144,900

DESIGN FOR A SIDE RAIL FOR TRUCK BODIES OR THE LIKE

Gottlieb Chris Boepple, Glendale, Calif.

Application March 5, 1945, Serial No. 118,264

Term of patent 14 years

(Cl. D14—16)

To all whom it may concern:

Be it known that I, Gottlieb Chris Boepple, a citizen of the United States of America, residing in the city of Glendale, in the county of Los Angeles, State of California, have invented a new, original, and ornamental Design for a Side Rail for Truck Bodies or the like, of which the following is a specification, reference being had to the accompanying drawing, forming a part thereof.

Fig. 1 is a front elevational view of a side rail for truck bodies or the like showing my new design;

Fig. 2 is a perspective view of the same; and Fig. 3 is an end elevational view.

I claim:

The ornamental design for a side rail for truck bodies or the like, substantially as shown.

GOTTLIEB CHRIS BOEPPLE.
